C. A. Snowdon

UNITED STATES PATENT OFFICE.

FRANK CHURCH, OF DUBOIS, NEBRASKA.

HAME.

SPECIFICATION forming part of Letters Patent No. 374,657, dated December 13, 1867.

Application filed July 12, 1867. Serial No. 244,216. (No model.)

To all whom it may concern:

Be it known that I, FRANK CHURCH, a citizen of the United States, residing at Dubois, in the county of Pawnee and State of Nebraska, 5 have invented a new and useful Improvement in Hame Attachments, of which the following is a specification.

My invention relates to adjusting attachments for use in connection with hames; and 10 it consists in the construction and arrangement of the parts of the same, as will be more fully hereinafter described, and pointed out in the claims.

The object of my invention is to provide a 15 hame having an attachment in connection therewith which will readily adjust the said hame for use in connection with varying sizes of collars, and to so construct the parts of the attachment that they will be simple and effective, strong and durable, readily understood and operated, attached in connection with hames now in use, and comparatively inexpensive in manufacture. I attain this object 20 by the attachment illustrated in the accompanying drawing, in which I have shown a perspective view of a hame with my attachment in connection therewith.

A indicates a hame of ordinary construction, having the back iron, *a*, and at the upper portion thereof a fluted spring-plate, *B*, 30 secured, which is engaged by a locking-lever, *B'*, mounted in the open end of a clip, *b*, which passes around the hame *A*. The locking-lever *B'* is provided with an operating handle or extension, *b'*, and an eccentrically-operating head, *b''*, which is adapted to engage with the flutes of the plate *B* in the adjustment at this point. Secured in an eye of the pintle *b''*, passing through the upper ends 40 of the clip *b*, and upon which the lever *B'* is pivotally mounted, a line-ring, *C*, is secured or attached. Between the hame and the inner portion of the rear side of the clip *b* the strap *C'*, which passes over the collar, is 45 clamped. When the lever *B'* is adjusted up or down and engages with the flutes of the spring-plate *B*, the clip *b* is in like manner carried upwardly or downwardly, as is also the line-ring *C*. It will thus be seen that the 50 whole adjustment is accomplished at one operation and any size of collar accommodated by such adjustment.

In the lower portion of the hame a hame-staple, *D*, is secured by passing in through the 55 back iron and riveted in the wood body of the

hame, as is the ordinary form of attachment. I have shown this staple *D* as having the inner side of its top cross-bar formed with a series of recesses, *d*, intersected by metallic projections *d'*, which are adapted to receive the staple *e* of a cockeye, *E*. This cockeye *E* is constructed in well-known form, having means, as *d''*, for attachment of the trace. This cock-eye is adapted to be removed from one of said recesses and placed in another, either to adjust it in an upper or lower position, as may be desired to change the line of draft, as will be readily understood; but I make no claim to this device.

By means of my improved attachment the 70 hame may be readily adjusted for use in connection with collars of varying sizes, and consequently with large or small animals.

The novelty and utility of my invention is obvious, and it is evident that the parts as 75 described could be slightly varied in their construction without departing from the nature and principle of my invention.

Having thus described my invention, I 80 claim—

1. The combination, with a hame, of the spring-plate secured to the upper portion thereof, the clamping-lever engaging with said plate, an open-ended clip passing around the hame and in which said clamping-lever is pivoted, and the line-ring secured to the clip, substantially as described.

2. The combination, with the hame, of the collar-strap *C'*, the open-ended clip passed around the said strap and the hame, and means, 90 substantially as described, for causing said clip to bind the strap to the hame, substantially as specified.

3. The combination, with the hame and the collar-strap *C'*, of the spring-plate secured to 95 the hame, the clip *b*, passed around the hame and the strap *C'*, and the clamping-lever pivoted in the clip *b*, and having a cam-head which engages the spring-plate, substantially as set forth.

In testimony that I claim the foregoing as my own I have hereto affixed my signature in presence of two witnesses.

FRANK CHURCH.
